CLAIM

The ornamental design for a support device for producing a dental implant, as shown and described.

DESCRIPTION

FIG. 1 is a top, front perspective view of a first embodiment of our design of the support device for producing a dental implant.

FIG. 2 is a front view thereof, which is identical to the rear view, the left side view, and the right side view.

FIG. 3 is a top plan view thereof.

FIG. 4 is a bottom plan view thereof.

FIG. 5 is an exploded view thereof, showing the support device for producing a dental implant in an environment of use.

FIG. 6 is a top, front perspective view of a second embodiment of our design of the support device for producing a dental implant.

FIG. 7 is a front view thereof, which is identical to the rear view, the left side view, and the right side view.

FIG. 8 is a top plan view thereof; and,

FIG. 9 is a bottom plan view thereof.

(Continued)

The broken lines depict environment and form no part of the claimed design.

1 Claim, 9 Drawing Sheets
